UNITED STATES PATENT OFFICE.

JOHN PORTEOUS, OF CINCINNATI, OHIO.

POP SAFETY-VALVE.

No. 848,202.

Specification of Letters Patent.

Patented March 26, 1907.

Application filed April 30, 1906. Serial No. 314,395.

To all whom it may concern:

Be it known that I, JOHN PORTEOUS, a citizen of the United States of America, and a resident of Cincinnati, county of Hamilton, 5 State of Ohio, have invented certain new and useful Improvements in Pop Safety-Valves, of which the following is a specification.

My invention relates to that class of pop safety-valves which are provided with a disk 10 for regulating the openings in the valve-body as an auxiliary means of varying the pressure at which the valve will be raised from its seat.

The object of my invention is a means for 15 adjusting the position of the valve in relation to the disk from the exterior of the housing.

Referring to the drawings, Figure 1 is a central sectional view of a pop safety-valve embodying my invention. Fig. 2 is an elevation thereof. Fig. 3 is a sectional view of the same, taken upon line v v of Fig. 1.

Referring to the parts, the housing consists of a hollow cylinder A, having an enlarged cylindrical chamber a , which is internally screw-threaded at its upper end to receive the cylindrical housing a' , which is to surround the valve-stem. Housing a' is internally screw-threaded at its upper end a^2 and exteriorly reduced in diameter. The 25 lower flange a^3 of housing a' has openings a^4 in it, which put the valve-chamber a in communication with the atmosphere.

The valve consists of a disk B, having a downwardly-projecting central hollow cone b , 35 wings B' for guiding it toward its seat, an upwardly-projecting and internally and exteriorly screw-threaded annular collar b' , and annular groove b^2 in its under surface. In the groove b^2 a series of perforations b^3 extend 40 to the upper face of the disk. The external threads of the collar b' are engaged by the threads of a regulating-disk C, whose under face is concave to fit over the disk B and whose periphery has cut in it a series of gear-teeth c . The cone b receives the lower cone-shaped end d of the valve-stem D, above the 45 end of which is an annular collar against which a nut d' bears, whose external screw-threads engage the internal screw-threads of 50 collar b' to hold the valve-disk upon the

valve-stem. Valve-stem D has a shoulder d^2 , between which and the tension-cap e a coiled spring E is held. The tension-cap is externally screw-threaded to engage the screw-threads upon the interior of the upper 55 end of the housing a' , the position of the tension-cap being regulated by nuts e' , which engages the external screw-threads of said cap and likewise hold the annular bracket F upon the upper reduced end of the housing 60 a' . Bracket F carries a lever f , which engages a slot in the upper end of the valve-stem D. The upper end of the stem is housed by a cap G, whose walls are slotted to permit the entrance of the lever into the 65 valve-stem. Chamber a has upon its side a journal-box a^6 , in which is journaled a worm H, whose teeth mesh with the teeth c upon the exterior of the disk C. The outer end h of the worm is made square to receive a 70 wrench for turning the worm and disk C.

For the main regulation of the pressure at which the valve will rise from its seat the spring E is provided, and to adjust the tension of this spring it is necessary to remove 75 the lever f from its bracket and then to remove the cap G, when access may be had to the regulating-cap e to vary the tension of the spring E. After the tension of the spring 80 E has been set the pressure at which the valve will rise from its seat may be auxiliarily regulated by changing the relative position of the disk C to the valve B. This may be done by actuating the worm H, which will open the ports b^3 to a greater or less degree. 85

I have found by experience that by means of operating this worm H a variation of several pounds may be made in the pressure at which the valve will rise from its seat.

What I claim is—

1. In a safety-valve, the combination of a valve-housing, a valve-seat within the housing, a valve consisting of a disk with an annular groove in its face and perforations leading into the groove, a regulating-disk seating 95 against the valve-disk to vary the size of the perforations, an actuating-arm journaled in the casing and engaging the regulating-disk and extending from the interior to the exterior of the housing for regulating the rela- 100

tive position of the regulating-disk and a spring for holding the valve to its seat.

2. In a safety-valve of the character described a housing, a valve-disk with perforations therein, a regulating-disk with external teeth and a worm journaled in the housing and engaging the teeth on the regulating-

disk for varying its position relatively to the valve-disk.

JOHN PORTEOUS.
